United States Patent Office.

EDWARD P. JONES, OF SHELL MOUND, MISSISSIPPI.

Letters Patent No. 96,703, dated November 9, 1869.

IMPROVEMENT IN DETACHING HORSES FROM CARRIAGES

The Schedule referred to in these Letters Patent and making part of the same.

To all whom it may concern:

Be it known that I, EDWARD P. JONES, of Shell Mound, in the county of Sunflower, and State of Mississippi, have invented a new and useful Improvement in Detaching Horses from Vehicles; and I do hereby declare that the following is a full, clear, and exact description thereof, reference being had to the accompanying drawing, in which—

Figure 1 is a plan view;

Figure 2, a transverse section, taken in the line $x x$ of fig. 1;

Figure 3, a rear elevation of a part of the whiffletree;

Figure 4, a transverse section, taken in the line $y y$ of fig. 1; and

Figure 5, an end view.

Like letters designate like parts in all the figures.

The nature of my invention consists in the peculiar construction of a whiffletree, by the operation of which the traces can be readily detached, in case of accident to the vehicle, or should the horse become unmanageable.

To enable those skilled in the art to make and use my invention, I will proceed to describe its construction and operation.

In the drawing—

A represents the whiffletree, which is pivoted to the cross-bar of the shafts.

The ends of the whiffletree have an extension of a hooked shape, their ends coming out even with the front of the whiffletree.

To the whiffletree are pivoted two spring-levers, B B. On each of these levers, near their outer ends, is an extension, in the outer end of which is a bolt or pivot, a, by means of which they are secured to the whiffletree.

C is a strap, the lower part of which is cut up some distance, thus making two ends, which are secured to the eyes b b, in the rear edge of the whiffletree. Its other

end may be brought up to or into the front part of the vehicle.

The two lower ends of this strap pass across the top of the whiffletree, and under the inner ends of the levers B B, in which are recesses for that purpose.

c c are inclined stops or projections on top of the whiffletree, near the outer edges of the strap C.

d d are straps secured to the cross-bar, and which pass around the ends of the whiffletree, to prevent too much play of the same.

D D are strips or bands that pass over the levers B B, and their ends are secured to the whiffletree.

Its operation is as follows:

To fasten the traces to the whiffletree, by drawing on the upper end of the strap C, the inner ends of the levers B B will be raised up above the stops c c, and the strap will then draw them back far enough to allow the end of the trace to be placed on their outer ends, and then draw the levers forward, until they have passed over and are in front of the stops c c, and the traces are securely attached to the whiffletree.

In case of accident, when it is desired to suddenly detach the horse from the vehicle, by pulling up the strap C, the inner ends of the levers B B are raised up above the top of the stops c c, when the force being exerted on the traces will immediately draw the outer ends of the levers forward, and throw the inner ends backward into the position shown in dotted lines in fig. 1, which will allow the traces to slip off of the ends of the levers.

Having thus fully described my invention, What I claim, and desire to secure by Letters Patent, is—

The combination of the whiffletree A, cleats c c, levers B B, and strap C, when constructed and operating substantially as shown and described.
